UNITED STATES PATENT OFFICE.

WILLIAM WHEELER, OF CONCORD, MASSACHUSETTS, ASSIGNOR TO THE WHEELER REFLECTOR COMPANY, OF BOSTON, MASSACHUSETTS.

ELECTRIC-LIGHT REFLECTOR AND ITS SUPPORT.

SPECIFICATION forming part of Letters Patent No. 254,523, dated March 7, 1882.

Application filed December 8, 1881. (No model.)

To all whom it may concern:

Be it known that I, WILLIAM WHEELER, of Concord, of the county of Middlesex and State of Massachusetts, have invented a new and useful Improvement in Electric-Light Reflectors and their Supports or Attachments; and I do hereby declare the same to be described in the following specification and represented in the accompanying drawings, of which—

10 Figure 1 denotes a side elevation, and Fig. 2 a top view, of a compound reflector provided with my invention, the nature of which is defined in the claims hereinafter presented. Fig. 3 is an inner end view of one of the reflector-sections with its clamps and hinge portions, to be described. Fig. 4 is an inner end view of the other reflector-section, showing its hinge portions.

The reflector shown is of double form—that 20 is, it is composed of two separate truncated or bonnet-shaped reflecting-sections, A B, arranged with their lesser ends or bases in contact. They are designed to reflect in opposite directions rays or beams of light from an electric burner arranged at or about at the center 25 of their common intersection. There project from each of the sections, at its inner end, two ears, a a b b. These ears are provided with two sets of hinge-joint tubes, c e d d d d, those marked 30 c being projected from the ears of one of the sections, while those marked d extend from the ears of the other section. Each of the tubes c is to go directly between and in line with two of the tubes d, and with such and a pin, e, passing 35 through the three tubes, is to constitute a hinge.

Each ear of the section A has a clamp, C, hinged to it at its outer edge, such clamp and ear being recessed to receive and span a cylindrical insulator, D, of india-rubber or other suitable material, through which tube one of the two vertical rods forming a part of the frames of the electric lamp, and used in this case for supporting the reflector also, is to pass. 40 Each clamp C is furnished with a screw, E, which goes through it and screws into the ear,

and is to set the clamp firmly to the insulating-tube, and that to the rod.

Each reflector-section is notched at its lesser end, as shown at f, in order that when the two sections abut against each other at their lesser ends there may be a vertical passage through them to receive the carbon pencils or means employed in the reflector for generating the electric light. On withdrawing either of the hinge-pins from its tubes the section B may be turned on the other pin in a direction away from the section A, in order for access to be had to the burner or parts composing it, the two sections being fastened together when the two pins are in place in the hinge-tubes.

In certain cases where the light is to be projected in one direction only, or when a double form of reflector, made in one entire part, is to be used, only one ear is provided upon each side of the reflector, and hence the hinges joining the two separable parts herein shown are dispensed with, the clamps remaining as shown and described.

I would remark that the two sections, instead of being provided with two hinges to enable them to be opened apart in either of two directions, may be hinged together so as to open apart in one direction only; but I prefer to have them double-hinged, as described and represented, for in such case either hinge, besides serving the purpose of a hinge, answers as a means of fastening the sections together.

I claim—

1. The two light-reflecting sections A B, hinged to each other, and provided with ears and clamps for holding insulating-tubes and confining them to rods, all being substantially as set forth.

2. A reflector provided with laterally-projecting ears and with clamps hinged thereto and furnished with screws, all being substantially and to operate as and for the purpose set forth.

Witnesses: WM. WHEELER.

R. H. EDDY,
E. B. PRATT.
